UNITED STATES PATENT OFFICE.

ALEXANDER G. RAYMOND, OF RIVERSIDE, CONNECTICUT.

CONTAINER.

1,302,710.

Specification of Letters Patent.

Patented May 6, 1919.

Application filed June 20, 1918. Serial No. 240,988.

To all whom it may concern:

Be it known that I, ALEXANDER G. RAYMOND, a citizen of the United States, residing at Riverside, in the State of Connecticut, have invented certain new and useful Improvements in Containers, of which the following is a specification, reference being had to the accompanying drawing, forming a part hereof.

10 The object of this invention is to provide a container for goods of various descriptions which must be protected against moisture, such as certain food products, certain drugs and chemicals, and gun powder, 15 which shall be light in weight, inexpensive to manufacture, especially as compared with metal containers, sufficiently strong to retain its shape in handling and to protect the contents, and wholly impermeable to 20 moisture. In accordance with the invention and inner lining or casing, of suitable form and dimensions, is covered with an interliner of metal foil, very thin and light but impervious to moisture, with contact of 25 metal to metal at all joints, and an outer casing. The inner lining or casing is sufficiently strong and stiff to furnish a reinforcement for the interliner of metal foil, which preferably has its seams sealed or 30 soldered, and the outer casing protects the rather delicate interlining of metal foil from abrasion. The invention will be more fully explained hereinafter with reference to the accompanying drawing in which it is 35 illustrated as embodied in a container of suitable form, and in which—

Figure 1 is a view of such a container in longitudinal section.

Fig. 2 is a detail view, also in longitudinal section but on a larger scale.

Fig. 3 is a detail view in transverse section on the plane indicated by the broken line 3—3 of Fig. 1.

It will be understood that the several figures of the drawing are somewhat exaggerated with respect to the relations of the several parts, especially the relation of the metal foil to the inner and outer casings.

50 The inner lining or casing *a* is made of any suitable material, preferably paper board wound upon a mandrel until the desired thickness of wall is secured, the several plies or layers being united by any suitable adhesive, preferably a waterproof adhesive, such as asphalt. This tubular in-

ner lining or casing *a* is provided at each end with an inset cap *b* which stiffens the inner lining or casing and assists in preserving its shape. The inner lining or casing is preferably shouldered internally, as at *a'*, at each end, for the purpose of receiving the cap *b* and each cap, if desired, may be held in place by an adhesive. The cutting away of the inner lining or casing *a* 60 to receive the cap not only furnishes a proper seat for the cap but permits the inner face of the wall to be perfectly smooth. It will be understood that one of the caps *b* is secured in place at one end of the lining 70 or casing *a*, the goods to be shipped, of whatever character they may be, are then introduced and the other cap is forced into place. The two caps *b*, *b*, may be secured in place within the lining or casing *a* by 75 means of any suitable adhesive.

When the inner lining or reinforcing or supporting form has thus been provided, there is applied to it, externally, an interlining *c* of thin metal foil, such as thin lead 80 foil. This is applied about the body of the inner lining or casing as a rectangular sheet with edges abutting, as at *c'*, and secured and sealed by solder, as at *c''*. Each end is then covered by a cap *d* of metal, also relatively thin, and stamped or pressed up, secured and sealed at its edge by solder, as at *d'*, to the metal interlining *c* with which it is in contact. The metal foil can be very thin, so far as its permeability is concerned, 90 and should be thin for the sake of lightness. It becomes necessary, therefore, to protect this relatively thin and delicate interlining from abrasion and for this purpose there is provided an outer lining or casing *e*, also 95 preferably made of paper or paper board by winding the same on a mandrel, with the plies secured by a suitable adhesive, preferably a waterproof adhesive, such as asphalt. At each end is then applied a cap *f* of any 100 suitable material, preferably secured in place by a suitable adhesive or crimped on.

Contact of the metal cap *d* with the metal interlining *c* may be secured in any suitable manner. As shown in the drawing the metal 105 interlining *c* is carried to the end of the tubular inner lining *a* and the metal cap *d* is extended beyond and pressed down over and into contact therewith and secured by solder. In this manner the metal interlining is made continuous over the ends as well as the sides and seamless and the container 110

becomes, as it is intended to be, impermeable at all points, air, moisture and gases being completely excluded from the contents.

- Reliance being placed for impermeability upon the interlining of metal foil which, for the sake of lightness, is made so thin as to be very delicate and incapable of retaining its shape, even under its own weight, it is necessary that the inner liner or inner lining or 10 casing *a* be relatively strong and stiff so as to provide a proper form and support for the relatively delicate metal foil, so as to reinforce the same and make it possible to form it, as well as to make it possible to fill 15 and seal this part of the container before it is introduced into the outer casing. Notwithstanding the provision of adequate support and reinforcement for the metal foil, such metal foil, if exposed, would be liable 20 to injury, with a loss of its desirable characteristic of complete impermeability and it is therefore necessary to provide an exterior casing and end caps in order to protect the metal foil against such injury.
- 25 It will be seen that the improved container may not only be very light in weight and inexpensive to manufacture, but is wholly impermeable to moisture and therefore furnishes complete protection for substances 30 such as various food products, various chemicals and gun powder, which must be protected absolutely against penetration of moisture from without. It will also be observed that with a proper treatment of the

interior surface, the improved container is 35 well adapted for the transportation of substances which are in a moist or even liquid condition.

It will be understood that the form and dimensions of the container and the character of material employed for the inner and outer casings as well as the relations of the several parts from the point of thickness may be varied as desired and will be determined in each instance by the character of 45 the goods to be shipped in the container.

I claim as my invention:

1. A container comprising a relatively rigid inner lining or casing of nonmetallic material, relatively stiff and light, a continuous and seamless interliner of metal foil laid upon the inner lining and covering the inner lining completely and having all its joints hermetically sealed, and an outer protective casing. 55

2. A container comprising a relatively rigid inner lining or casing of nonmetallic material having inserted end caps, a continuous, hermetical interliner of metal foil laid upon the inner lining or casing with end 60 caps of like material in contact therewith and hermetically sealed thereto, and an outer protective casing also provided with end caps. 65

This specification signed this 18th day of June, A. D. 1918.

ALEXANDER G. RAYMOND.
